UNITED STATES PATENT OFFICE

2,026,633

APPARATUS FOR SEPARATING MATERIALS
BY FLUID STREAMSMack E. Haworth, Pittsburgh, Pa., assignor to
The Jeffrey Manufacturing Company, a cor-
poration of Ohio

Application May 26, 1931, Serial No. 540,059

15 Claims. (Cl. 209—502)

This invention relates to the control of fluid streams; to an arrangement whereby a constant weight or buoyancy of fluid stream can be delivered irrespective of changes in pressure, temperature, humidity and/or resistance; and particularly to an arrangement whereby certain definite predetermined resistances may be automatically or otherwise maintained through the bed of coal or other mixtures of materials upon a deck or other pervious surface and being acted on by the fluid stream; and to the control of certain portions of the fluid stream within the system. The invention also relates to the automatic regulation of fluid streams for purposes other than the separation of various mixtures of materials, such as the parallel operation of a plurality of blowers operating in connection with a common system of ducts; and to the automatic regulation of drafts for boiler furnaces, cupolas, etc.

This invention is an enlargement upon certain portions of my companion application Serial No. 516,632, filed Feb. 18, 1931 for Fluid stream control.

In my work and study on fluid stream control and particularly in connection with the separation of mixtures of solid materials containing constituents of different specific gravities by means of fluid streams, I have found existing apparatus and methods unreliable, complicated and non-uniform. Many manual operations were necessitated which depended solely upon the judgment and skill of the operator with the concomitant disadvantages appreciated by those skilled in this field. Such, furthermore, required close and exacting attention and were insufficiently sensitive to changing conditions.

The above and other defects and disadvantages have been overcome by my present invention, the obviation of which constitutes one of the objects of the present invention.

It is another object of this invention to provide a sensitive, readily controllable arrangement for increasing the efficiency of the separation above indicated.

A further object is to effectuate means for delivering a constant weight or buoyancy of fluid stream regardless of variations in the surroundings.

Additional objects lie in the features of control hereinafter specified and in automatic regulatory means to be described.

Other and still further objects and advantages will be understood by those skilled in this art

or will be referred to in the appended description.

In the accompanying drawings, I have illustrated, in Fig. 1, more or less schematically an arrangement for securing the advantages of my present invention and this is to be considered as exemplary only.

Fig. 2 is a wiring diagram of the control for any one of the damper motors.

I have found by research and experimentation that certain results can be obtained in the separation of materials by regulating the fluid streams in various portions of the separatory deck to values of buoyancy different from those in other portions of the deck.

I have also found that the regulation of the fluid stream in one or more sections of the deck changes the fluid stream flow through other sections of the deck unless certain corrections are made to bring the fluid streams through the other sections to their former values, when the desired regulation is accomplished in all sections.

As illustrated in Fig. 1, a mixture of materials to be separated is fed onto the reciprocatory deck 10 through which a fluid stream is flowing from a suitable source. The deck may be divided into compartments or sections such as 11—12—13—14—15—16, etc. and means (not shown in this application) provided for regulating the flow of the fluid stream through each section independently of each other section. The value of the fluid stream, its buoyancy etc., are regulated according to the thickness of the bed of materials upon the deck as described in my copending application S. N. 516,632. The reciprocatory means is diagrammatically shown at 17.

So long as the thickness of the bed remains at a constant value the buoyancy of the fluid stream should remain unchanged for constant efficiency of separation. Under constant conditions of temperature, barometer, moisture, resistance and pressure the value of the fluid stream remains constant if the thickness of the bed remains unchanged and the mixture of materials remains substantially the same, i. e., the mixture does not change sufficiently to affect the buoyancy required for free settling.

When there is a change in any of the variable items,—temperature, barometer, moisture, resistance or pressure,—it becomes necessary to change the volume of fluid stream per unit of time in order to maintain the same effective buoyancies. Again, if the moisture content of the materials upon the deck varies appreciably there will be a change in the volume of fluid stream, by reason

of inherent characteristics of blowers, unless a correction is applied to maintain the volume required to produce the desired buoyancies. Also, if there is a change in the resistance of the air or fluid ducts by reason of changes in the volume of the fluid stream there will be a change in the fluid stream through the materials upon the deck unless a correction is applied, this also by reason of inherent characteristics of the blowers. Further, and for the same reason, if there is any change in the resistance of the dust arresters, dampers, etc. to the flow of the fluid stream there will be a change in the volume of the fluid stream through the materials upon the deck.

I have found that it is possible to make all the corrections for any change in any of the variable items enumerated by new and novel means for the control of the fluid streams, some of which are referred to in my copending application Serial No. 516,632, and further that the corrections can be made automatically with the blower or blowers operating at a constant speed, a desirable operation because of the simplicity of the drives and lower cost of motors driving the blowers.

As illustrated in the drawings, a duct 18 connects the deck hood 19 with the blower 20 of any suitable type and is provided with a damper 21. A duct 22 connects the blower 20 with the dust arrester 23 and may or may not be provided with a damper 24 similar to damper 21. The blower is provided with a bypass 25 which is fitted with a damper 26 similar to dampers 21 and 24.

The blower 20 is operated at a fixed speed and against a predetermined total pressure. Damper 21 is set to introduce a certain value of artificial resistance which comprises a part of the total blower resistance. Damper 26 is regulated to permit only the desired volumes of fluid stream to be "short circuited" from the discharge or pressure side of the blower to the suction side.

An electrically controlled manometer M' or other instrument or equipment for measuring the pressures developed in the fluid stream is connected to the inside of the deck hood so as to measure the difference in pressure between the inside of the hood and atmospheric. Another similar instrument or equipment M² is connected to either side of the blower 20 in order to record the total combined suction and discharge heads or total pressure against which the blower operates.

The dampers 21, 26, and 24 when the latter is used, are operated by means of suitable motors 27, 28, 29 which when operated in one direction close the duct or restrict the flow of fluid stream therein and when operated in the opposite direction open the duct or reduce the restriction to the flow of fluid stream therein. Motors 27, 28, 29 are of the reversible electric type, for example, and have the pinion gears 30, 31, 32 meshing with racks 33, 34, 35 suitably connected to dampers 21, 26, 24 respectively. The dampers may be suitably mounted in their respective ducts and may comprise any desirable construction per se, the drawings showing co-operable pairs of damper elements, as an example, both of which are secured to the racks 33, 34, 35, as shown.

When the damper 24 is used in place of the damper 21 or in addition thereto, the motor 29 for operating the damper 24 may be controlled

by means of apparatus the same in construction as that used for the motor 27 and operated by similar mechanism connected to the hood 19. Or if desired the relays 48, 49 may be used for controlling separate or additional "forward" and "reverse" electro-magnetic switches for the controlling of the supply of current from electric supply mains to the motor 29 so that at the same time that the switch 45 effects the operation of the motor 27 the motor 29 will be likewise operated.

A mixture of material of a certain thickness of bed is fed onto previous deck 10 for the purpose of separating the various component parts by taking advantage of the difference in specific gravities of the component parts. By determination it is found that in order to produce a condition in the mixture whereby "free-settling" takes place in the section 11 of the deck near the feed end, a difference of pressure amounting to "x" inches of water is required for settling the heaviest gravity material to the lower strata of the bed. The difference in pressure required in other sections for settling the lighter gravity materials or finer materials may be less than the difference in pressure required for settling the heavier gravity materials and, if so, sufficient artificial resistance may be inserted under sections, 12, 13, 14, 15, 16, etc., to take up the difference between the pressure required at section 11 and the pressure required in the other sections. Hence the difference in pressure between the area over any section of the deck, and atmospheric has the same value, while at the same time the pressures acting upon the mixtures of materials in various portions of the deck are different, the differences amounting to the value of artificial resistances inserted under the various sections. The artificial resistances may be introduced by means of louvres of the conventional types (not shown), by means of two matched perforated plates one sliding upon the other so as to permit any desired portion of the area of under the deck to be open to the flow of air, from zero percent of open area to the maximum allowed with all holes fully registering, or other suitable arrangements (not shown).

Having determined the pressure or water gauge required to produce the buoyancies for "free-settling", fluid stream pressure equalizing pipe 36 is connected from the inside of the hood 19 over the deck 10 to deck pressure regulator 37 which comprises two inverted bells 38 connected by balance bar 39 and immersed in a suitable liquid 40. The balance bar 39 is balanced on a pivot point 41 and counterbalanced at 42. Pressure pipe 36 is connected to one bell and a pipe 43 connects the other bell to the atmosphere. The bells are so designed as to register the difference in pressure exerted upon them by pressure pipe 36 and atmospheric pipe 43 in inches of water, inches of mercury or other units of pressure best fitting the conditions or pressures obtaining. Liquid 40 is contained in a suitable tank or receptacle 44.

The balance bar 39 of the regular 37 is fitted with an arm 45, or other suitable arrangements are provided, for operating contacts 46, 47. If a difference of pressure of "x" inches of water is required the contacts are so arranged that one contact 46 is just above "x" inches of water and the other contact 47 just below "x". Any change in the value of "x" indicates a change in the pressures through the deck and will result in a

movement of the bells 38 and arm 45. If the pressure tends to increase, arm 45 will close the upper contact 46 which through suitable relays 48 illustrated will operate motor 27 and close damper 21 restricting the flow of air through duct 18 and the deck 10 until the difference in pressure has reduced to the original value "x". If the pressure tends to decrease, arm 45 will close the lower contact 47 and in a similar manner operate motor 27 in the opposite direction opening damper 21 to increase the flow of air through duct 18 and the deck 10 until the difference in pressures has increased to the original value "x".

15 Relays 48 are provided to cause damper 21 to move in small increments to prevent "hunting" for each pressure change.

20 Damper 21 not only provides the correction in air volumes for changes in pressure occurring through the deck, but maintains the predetermined pressure through the deck in a similar manner irrespective of: changes in resistance in ducts 18 or 22; changes in resistance in dust arrester 23; or changes in air densities by reason 25 of a change in temperature, barometer or humidity.

25 By maintaining a predetermined difference in pressure between the area over the material bed on the deck and the atmosphere, corrections are automatically applied for a change in air density as follows: Air of a certain density flowing at a certain velocity through a bed of materials of a certain thickness will develop a certain difference in pressure or water gauge "x". Resistance to the flow of air is dependent upon the density of the air and is proportional to the density. As the density of the air increases the resistance to its flow increases, the exponent of increase depending upon the velocity of the flow. Therefore, as the density of the air increases or decreases, the resistance to the flow increases or decreases and the difference in pressure, or water gauge increases or decreases. As the increase or decrease attempts to take place the deck pressure regulator 37 and contacts 46, 47 act to rotate the motor, operating damper 21 in the direction required to decrease or increase the pressure to bring it to the original predetermined value "x".

30 Similarly, for any attempted change in the value "x" for any reason other than a change in air density, such as an increase in the moisture content of the materials on the deck which would increase the resistance to the flow of air and tend to reduce the air stream, or vice versa; a change in the resistance to the flow of air in duct 18 or 22; a change in dust arrester resistance etc. etc., damper 21 is operated in the proper direction to correct for the changed conditions thereby maintaining the predetermined value "x".

35 60 Therefore, no attempt is made to provide any certain flow of air through the deck as measured in cubic feet per minute, the basis upon which air streams have been provided heretofore, irrespective of the variable and changing conditions mentioned, but provisions have been made for accurately providing the air streams required for producing and maintaining the buoyancies required for "free-settling", the conditions required for efficient and consistent separation by taking 65 advantage of the difference in specific gravity of the various component parts of the mixture of materials.

70 75 The value "x" referred to may be any value desired in inches of water, inches of mercury, pounds per square inch, etc. and the setting may

be adjusted to any desired value within the limits provided for any particular installation with the apparatus in operation or at rest.

A blower operating at a constant speed and against a constant head will produce a constant volume of air if measured in cubic feet per minute provided the density of the air does not change. The volume per unit of time varies, however, with changes in density, the change being directly proportional to the change in density.

10 In order to provide a blower operating at constant speed, a speed is adopted that will provide an excess of air over the range of operation for which the separating table is provided, the excess being transferred from the discharge to the suction side of the blower until such time as a portion or all of the excess is required through the system.

15 In order to provide for the blower operating at a constant head, two pressure pipes 49 and 50 20 are provided to connect the suction and discharge sides of the blower 20 with a fan or blower pressure regulator 51, constructed similarly to the deck pressure regulator 37 and operating in a similar manner. The "prime" numerals indicate 25 each similarities. The total pressure or head against which the blower operates is predetermined and the volume of air produced at that pressure predetermined so as to provide an excess over the volumes normally required to maintain the difference in pressure "x" through the deck previously described. The difference between the volume required for pressure "x" under normal conditions and the volume produced by the blower under normal conditions is transferred 35 from the pressure side to the suction side of the blower by means of bypass 25.

20 40 If the total pressure against which the blower has been designed to operate tends to increase or decrease, there will be a corresponding tendency for the pressure "x" through the deck to decrease or increase. However, through deck pressure regulator 37, damper 21 is adjusted to correct for the change in total pressure or head; consequently, the total head is reduced to the 45 predetermined value.

25 50 Due to leaks or air inlets on the suction side of the blower for dust suppression or other purposes, or outlets on the discharge side for desirable or unavoidable reasons, the volumes of air passing through ducts 18 and 22 may be changeable while at the same time the volumes passing through the deck may be unvariable. Therefore, with constant deck volumes variable total volume may be desirable. Therefore, the 55 bypass serves three purposes, viz: to take care of the excess volumes produced by the blower, to maintain a constant head against which the blower operates, and at the same time provide variable volumes through the system with the 60 blower operating at constant speed against a constant head.

65 70 While damper 21 is adjusting itself to correct for any change in the total head against which the blower operates, fan pressure regulator 51 65 acts to energize motor 28, operating damper 26 in the bypass, opening or restricting the same to permit the excess volume to pass through the bypass not required through the deck for developing the difference in pressure "x", or for dust 70 suppression or other purposes through inlets on the suction side or through outlets to the atmosphere on the discharge side, or for special purposes from the pressure side to the suction side through ducts other than the bypass.

The hoods 19 over sections 11 to 16 are somewhat constricted or convergent as at 52, thus acting as artificial resistances. As is known, flexible side pieces 53 of suitable fabric or other material are used for the usual purposes. Inasmuch as the fluid circulation sometimes tends to go in the wrong direction at the deck edges due to inflow of air, I may provide a pipe 54 leading from the deck edge to the hoods 19 thus obviating such tendency. This enhances efficient separation. Pipe 36 extends through the several hoods and has an outlet 55 in each. These outlets 55 are of the well known type which make the pressure responsive device M' respond to any changes in the velocity head of the air flowing through the bed on deck 10.

Where blowers are used for producing a constant weight of air per unit of time against variable resistances; or where a plurality of blowers operating against the same or different total heads are connected to a common duct a similar arrangement of dampers, or bypass ducts fitted with a damper or dampers, and bypass ducts fitted with dampers may be used to assure constant and efficient operation.

The details of the control for the motors 27 and 28 are shown diagrammatically in Fig. 2, which shows, for purposes of illustration, the connections between the pressure regulator 37 and motor 27. It will be understood that the connections between the pressure regulator 51 and motor 28 are in all respects similar, and that motor 29 may be provided also with a like control.

When the pressure in the bell 38 increases so as to lift arm 45, contact 55 on this arm will engage contact 46 and a circuit will be established from current supply line conductor L₁ through conductor 56, contact 55, contact 46, conductor 46a, coil 57, conductors 58, 59 and 64, back to conductor L₂ of the supply line. Coil 57 is thus energized, closing the left-hand relay 48 as viewed in Fig. 2, and establishing a circuit from supply line conductor L₃, through conductor 60, conductor 60a, left-hand relay 48, conductor 61, coil 62, conductor 63 and conductor 64, back to supply line conductor L₂.

This energizes coil 62 and closes the contacts of switch 65, making a circuit through the motor 27 from the power line conductors L₁, L₂, and L₃ to operate the rotor 66 of the motor 27 forwardly, to close the damper 21.

When the pressure under bell 38 drops sufficiently to allow the contact 55 to engage the lower contact 47, the motor 27 is operated in the reverse direction, effecting a closing of dampers 21.

When contacts 55 and 47 close, circuit is made from the supply line conductor L₁ through conductor 56, contacts 55 and 47, conductor 67, coil 68 of the right-hand relay 48, conductor 69, conductors 59 and 64 to the supply line conductor L₂.

The right-hand relay 48 closes, establishing a circuit from supply line conductor L₃ through conductor 60, conductor 70, right-hand relay 48, conductor 71, coil 72 of motor reversing switch 73, conductors 74, 63 and 64 to the supply line conductor L₂.

This closes switch 73 and establishes a circuit through the motor from the power supply line, in an obvious manner, to operate the rotor 66 in the reverse direction so as to close the dampers 21.

It will therefore be seen that the total resistance to the flow of air through the system will

be automatically adjusted responsive to variations in the conditions of the air stream and in the resistance in the bed to the flow of the air stream through the bed, so that the buoyancy of the air stream in the bed will remain constant, 5 irrespectively of such variations.

I have worked with other systems not so arranged and have measured the volumes produced by blowers at constant speed connected to common ducts. I have observed one blower in a 10 duct developing a part of its designed volume and at the same time, another blower producing only a small portion of its designed volume. With the apparatus described the blowers can be fitted in a similar manner to that described so that 15 adjustments will be automatically made for any of the varying conditions described.

For boiler plants, cupolas, etc. where oxygen is the element desired in the air, blowers fitted with the apparatus described are equipped to 20 produce the desired weight of oxygen per unit of time and they produce that weight of oxygen per unit of time irrespective of any changes that take place in the density of the air or the pressures that take place in the system through 25 which the air passes.

What I claim as new and desire to secure by Letters Patent is:

1. In a system of the character described, a deck, hoods over said deck, means for creating 30 suction over said deck between said deck and said hoods, and a connection to said hoods from a point above said deck at the edge thereof to provide outward rather than inward flow at said deck edge.

2. In a system for pneumatically separating a mixture of material, the combination of a deck on

which said materials are supported, for separation, of suction hoods over said deck, a duct connected to said hoods at one end, a dust arrester connected to the other end of said duct, a blower in said duct, a by-pass leading from the discharge side of said blower to the suction side thereof, a variable resistance in said duct, a variable resistance in said by-pass, pressure responsive means connected between said first variable resistance and said hoods for automatically maintaining said suction in said hoods as to maintain substantially constant the buoyancy of the air flow through said bed, and pressure responsive 50 mechanism operatively associated with said variable resistance in said by-pass for short circuiting a portion of the fluid stream generated by said blower in said duct.

3. In a system for separating materials by fluid streams, the combination with a tank, of liquid in

said tank, a pair of inverted bells in said liquid, a pivoted balance bar connecting said bells, a counterweight connected to one end of said

balance bar, a motor controlled by movements of 60

said balance bar, a bed for supporting the material to be separated, means comprising a constant speed blower and a duct for effecting a

flow of air through said bed, an electrically operated damper for said duct controlled by said

motor, and a pipe connecting said duct to one of 65

said bells, and a pipe connecting the other bell to the atmosphere.

4. In a system for separating materials by fluid streams, the combination with a bed for support-

ing material to be separated, of means for main-

taining substantially constant the buoyancy of

air flow through said bed, regulating mechanism

comprising an electrically operated damper, a

motor for controlling said damper, and air pres-

35

40

45

70

75

sure responsive mechanism responsive to the velocity head of the air flowing through said deck for automatically controlling said motor.

5. In a system for pneumatically separating materials, the combination with a duct, of a blower in said duct, a by-pass connecting the suction and discharge sides of said blower, and means automatically operable by the difference of pressure between said suction and discharge 10 sides to control the flow through said by-pass.

6. In a system for separating materials by fluid media, the combination with a blower for generating a fluid stream, of a by-pass for said blower, a variable resistance in said by-pass, and mechanism responsive to variations of difference of 15 pressure between the suction and discharge sides of said blower for controlling the resistance in said by-pass to maintain constant the effective volume of air supplied by said blower for the 20 separation of materials.

7. In a system for separating materials by fluid media, the combination with a duct, of a fluid stream generator for said duct and comprising a blower and a by-pass about the same, a variable 25 resistance in said by-pass, and automatic mechanism connected to said duct on opposite sides of said generator to vary said resistance to maintain substantially constant the volume of the fluid stream in said duct.

30 8. In a system for supplying a fluid stream at constant pressure and volume to a bed of materials, the combination with a support for such materials, of a duct communicating with the bed of materials, means dependent upon pressure in 35 said duct for automatically regulating such pressure, a source of fluid pressure supply in the duct, a by-pass around said source of supply and communicating with said duct, and means dependent upon pressures in said duct for automatically controlling the flow through said by-pass to effect regulation of the volume of the fluid supplied to 40 said bed of materials.

9. In coal-cleaning apparatus, the combination with a deck adapted to support a bed of comminuted coal and impurities, of means for vibrating 45 said deck, a duct communicating with the bed of material, means comprising a constant speed blower for generating the fluid stream through said bed of coal and impurities to effect separation 50 of the coal from the impurities by stratification, means dependent upon fluid pressure in said duct for automatically regulating such pressure, and automatic mechanism associated with said constant speed blower to automatically regulate 55 the volume of fluid passing through said bed.

10. In a system for separating materials by fluid media, the combination with a duct, of a fluid stream generator for said duct and comprising a blower and a by-pass about the same, a variable 60 resistance in said by-pass, and automatic mechanism connected to said duct on opposite sides of said generator to vary said resistance to maintain substantially constant the pressure drop across said generator.

11. In a system for separating materials by fluid media, the combination with a bed adapted to support said materials, a duct connected to said bed, a fluid stream generator feeding said duct comprising a blower and a by-pass for the 5 same, a variable resistance in said duct between said blower and said bed, a second variable resistance which is located in said by-pass, means responsive to the pressure drop across the bed and means responsive to the pressure drop across 10 the generator, whereby said first and second variable resistances may be controlled as dictated by said responsive means.

12. In a system for separating materials by fluid media, the combination with a bed adapted 15 to support said materials, a duct connected to said bed, a fluid stream generator feeding said duct comprising a blower, means for maintaining constant the buoyant action of said fluid media regardless of changes in the density thereof 20 comprising, means for indicating a change in the buoyant action of said fluid due to either a change in the density or in the velocity thereof through said bed, and means for adjusting the flow of fluid through said bed, to maintain said 25 condition of constant buoyancy.

13. In a system for separating material by fluid streams, the combination with a bed for supporting material to be separated, of means for maintaining substantially constant the buoyancy 30 of air flow through said bed comprising, regulating mechanism including a damper, means for operating said damper, and means responsive to the velocity head of the air flowing through said deck whereby the damper may be adjusted 35 to maintain said condition of constant buoyancy.

14. In a system for pneumatically separating a mixture of material, the combination with a deck on which said materials are supported for separation, of a suction hood over said deck, a 40 duct connected to said hood at one end, a dust arrester connected to the other end of said duct, a blower in said duct, a by-pass leading from the discharge side of said blower to the suction side thereof, a variable resistance in said duct, 45 a variable resistance in said by-pass, means including pressure responsive means associated with said hood whereby said first mentioned resistance may be adjusted to maintain substantially constant the buoyancy of the air flow 50 through said bed, and means including pressure responsive means associated with said duct whereby the second named resistance may be adjusted for short-circuiting a portion of the fluid stream generated by said blower in said duct. 55

15. In a system for pneumatically separating materials, the combination with a duct, of a blower in said duct, a by-pass connecting the suction and discharge sides of said blower, and means for controlling the flow through said by-pass including means operable by the difference of pressure between the suction and discharge 60 sides of the blower.

MACK E. HAWORTH.
